RETORT FOR THE DISTILLATION OF COAL

Harold Stevens, Cincinnati, Ohio, assignor, by
mesne assignments, to Harold Stevens, trustee

Application February 6, 1931. Serial No. 518,849

2 Claims. (Cl. 202—99)

This invention relates to retorts for the distillation of coal and is especially useful where the heat required for distillation is provided by electrical energy.

One of the primary objects of the invention is to prevent electrical leakage.

The foregoing, together with such other objects and advantages as may be incident to the invention, will appear more clearly in connection with the following description of a preferred embodiment of my invention shown in the accompanying drawing, wherein—

Fig. 1 is a vertical section through the retort, and

Fig. 2 is a fragmentary vertical sectional view drawn on an enlarged scale and illustrating a detail of the invention.

Referring now to Fig. 1, it will be seen that the retort generally indicated at 7 is upright and is comprised of an inner refractory wall 8, an outer metallic shell 9 and an intermediate filling 10, preferably of dense material. The retort is provided with a door 11 at the bottom and with means (not shown) at the top for introducing the charge of coal.

Initiation of the heat is brought about by an electrical resistor means 12 such as a tubular member filled with coke. The retort has a low potential electrode 13 and a high potential electrode 14 for the resistor or starting fuse.

While the construction of the retort is not one which tends to produce electrical leakage, this may sometimes occur and in order to make certain that it will not occur or that it will be capable of being controlled, I preferably construct the metallic shell 9 in two or more sections with a gap or gaps such as the one shown at 15 therebetween providing electrical insulation joints.

Referring more particularly to Fig. 2, it will be seen that the bottom section of the shell and the top section of the shell have brackets 16 and connecting bolts 17. The connecting bolts are insulated as at 18 in the upper brackets, the insulation sleeve being held in place by any suitable means such as taping 19. An annular member 20 is supported on the lower brackets as by welding and provides a space within which insulating material 21 may be carried, such insulating material closing the gap. If desired, the upper section of the shell may be reinforced by a sleeve 22.

The liquid products of distillation drain off at 23 and the gaseous products may be drawn off at any desired point. A plurality of offtakes

14 are shown in the side wall of the retort for this purpose, and an additional offtake 25 appears at the bottom.

Attention is called to the fact that various features herein disclosed are described and claimed in one or more of the following of my copending applications: Serial No. 489,530, filed October 18, 1930, Serial No. 489,532, filed October 18, 1930, Serial No. 489,534, filed October 18, 1930, Serial No. 489,535, filed October 18, 1930, Serial No. 489,536, filed October 18, 1930.

I claim:—

1. Coal distillation apparatus including an elongated refractory lining defining a retort chamber, electrode means at opposite ends of said chamber for the passage of current through the coal to be distilled, and an elongated metallic shell surrounding said lining, said shell being composed of two spaced sections together with insulating material at the space between said sections, bolts securing the sections to each other and insulation for the bolts.

2. Coal distillation apparatus including an elongated refractory lining defining a retort chamber, closure means at opposite ends of the chamber, electrode means fastened to the closure means, said electrode means being exposed to the coal to be distilled in order to provide for passage of an electrical current therethrough, and an elongated metallic shell surrounding said lining, the shell being annularly split intermediate its ends whereby to provide an annular gap for insulation of the two portions of the shell and thus prevent leakage of current between the electrode means, together with means spanning said gap for securing the two parts of the shell together, the last mentioned means including insulated securing bolts.

HAROLD STEVENS.
